UNITED STATES PATENT OFFICE.

JULIO G. NEGRETE, OF HABANA, CUBA.

FOLDING BED.

1,234,067.

Specification of Letters Patent.

Patented July 17, 1917.

Application filed March 7, 1916. Serial No. 82,773.

To all whom it may concern:

Be it known that I, JULIO G. NEGRETE, a citizen of the Republic of Cuba, residing at Habana, in the Province of Habana, Cuba, 5 have invented certain new and useful Improvements in Folding Beds; and I do hereby declare the following to be a full, clear, and exact description of the invention, such as will enable others skilled in 10 the art to which it appertains to make and use the same.

This invention relates to improvements in beds, and particularly to folding beds.

One object of the invention is to improve 15 and simplify devices of this character.

Another object is to provide a bed of this 20 character which can be quickly and easily let down into operative position or raised into inoperative position and which combines therewith novel means for holding the bed firmly in such position.

Another object is to provide a bed of this 25 character which is equipped with a novelly constructed and arranged mosquito canopy for the bed, which can be quickly and easily moved into and out of operation.

Other objects and advantages will be apparent from the following description when 30 taken in connection with the accompanying drawing.

In the drawing:

Figure 1 is a front elevation of my improved bed, in open position;

Fig. 2 is an end view of the same in open 35 position;

Fig. 3 is an end view showing the bed in closed position;

Fig. 4 is a front elevation showing the bed in closed position;

Fig. 5 is a front elevation of the upper 40 portion of the bed showing one of the canopy supporting arms in extended position;

Fig. 6 is a horizontal section on the line 45 6-6 of Fig. 2;

Fig. 7 is a detail sectional view of one corner of the bed.

Referring particularly to the accompanying drawing, 10 represents a pair of uprights formed with the longitudinally extending slots 11. Suitable supporting feet 12 are secured to the lower ends of these uprights, the lower ends being connected by a bar or rod 13. Connecting the upper ends 50 of the uprights is a transverse shelf 14, at the rear edge of which is secured a verti-

cally extending ornamental strip 15. Secured to these upper portions of the uprights, and extending forwardly and lengthwise over the shelf is a rod 16 on which are 60 mounted the curtains 17, by means of the sliding rings 18. A frame including the end members 19 and the side members 20 has mounted thereon the spring bed bottom. This bottom includes the transverse end strips 22, and the wire fabric 23 connected at its ends to the said transverse strips. One of these strips, designated by the numeral 22' is connected to the adjacent end strip of the frame by means of the tension screws 70 24 which extend through said strips and are adapted to be turned to move the end strip 22' toward and away from the end strip of the frame, thus tightening or loosening the wire fabric. Pivotaly mounted on the side, 75 at each end of the side strip is an obtuse angular metal strip 25. Extending transversely of each end of the bed is a rail 26, one forming the head-board, and the other the foot-board of the bed. To the ends of 80 these rails are rigidly connected the remaining ends of the before-mentioned strips 25, thereby pivotally supporting the said rails for movement into vertical position on the end strips of the frame at times, and to lie 85 on the top of the bed bottom when the bed is to be folded, at other times. The ends of the inner sides of the frame are provided with the longitudinally extending pins 27 which are arranged to slide vertically in the 90 slots of the uprights 10. In the rear wall of each of the slots, and at a proper height from the floor there is formed a downwardly and rearwardly inclined notch 28, into which the pin is adapted to be engaged 95 to support that side of the bed in proper position, notched plates 28' being secured to the uprights and in registry with the notches of the uprights. At the corners of the outer side of the bed frame are the 100 pivoted legs 29, said legs being provided with eyes or loops 29' for engagement of the pivoted hooks 30 carried by the side members 20 of the frame, to brace the legs in proper bed supporting position. Pivotally connected to the end members 22 of the 105 bed frame, and to the inner faces of the uprights are the metal supporting arms 31.

In folding the bed, the head and foot boards are folded down onto the bed, the 110 legs released from the hooks and folded against the bottom of the bed frame, after

which the inner side of the bed frame is raised slightly and moved outward so as to disengage the pins from the notches of the uprights. The pins will then move down 5 toward the bottoms of the slots, as the outer side of the bed is raised, the pivoted supporting arms 32 holding the inner side of the bed so that it will swing on said arm. After the bed frame is swung up into position 10 between the uprights 10, pivoted buttons 32 are swung so as to engage in the slots of the uprights and thus hold the bed frame in such position. The before-mentioned curtains 17 are then drawn into position in 15 front of the bed so as to completely hide the bed.

Pivottally mounted on the underside of the shelf, and at each end is an arm 33, which is adapted to be swung outwardly 20 over the bed, when said bed is in open position, and to engage with a spring detent 34

also carried by this shelf. Connected to these arms is a canopy 35 formed of mosquito netting which, when the arms are swung outwardly, will completely envelop 25 the bed, and prevent access of mosquitos.

What is claimed is:—

A folding bed comprising a stationary upright frame including longitudinally slotted side members, a bed frame pivotally supported for movement into and out of the frame, projections on the bed frame slidably disposed in the slotted members, foldable legs for the bed frame, and pivoted latches carried by the bed frame for engagement in 35 the slotted side members.

In testimony whereof, I affix my signature, in the presence of two witnesses.

JULIO G. NEGRETE.
